by Robert B. Burlin

UNITED STATES PATENT OFFICE.

LESLIE H. BURLIN, OF CHICAGO, ILLINOIS.

DESIGN FOR A BRACKET FOR LAMP AND LIKE STANDS.

Application filed October 10, 1924. Serial No. 11,015. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for Bracket for Lamp and like Stands, of which the following is a specification, reference being had to the accompanying drawing, forming a part thereof.

The figure is an elevation of a bracket for lamp and like stands showing my new design.

My bracket for lamp stands is made and sold as a complete and separate article of manufacture.

I claim:

The ornamental design for a bracket for lamp and like stands, as shown.

LESLIE H. BURLIN.
